UNITED STATES PATENT OFFICE.

WALTER L. STINE, OF NILES, CALIFORNIA.

AUTOMATIC GREASE-CUP.

1,142,283.

Specification of Letters Patent. Patented June 8, 1915.

Application filed November 7, 1912. Serial No. 730,037.

To all whom it may concern:

Be it known that I, WALTER L. STINE, citizen of the United States, residing at Niles, in the county of Alameda and State of California, have invented certain new and useful Improvements in Automatic Grease-Cups, of which the following is a specification.

This invention relates to improvements in grease cups for machine parts having a to and fro movement.

The invention consists in providing a feeding element adapted to be moved in opposite directions to feed the lubricant by reason of the to and fro movement of the machine part to which the lubricant cup is attached.

By reason of my improved construction the necessity for adjusting the usual cap of the cup, downwardly therein, to force out the lubricant, is entirely avoided.

Further objects and advantages of the invention will be more fully described in connection with the accompanying drawing and will be more particularly pointed out in and by the appended claims.

In the drawing:—Figure 1 illustrates the device of my invention applied to the connecting rod of a crank. Fig. 2 is a longitudinal sectional view of my improved lubricant cup.

Like characters of reference designate similar parts throughout the different figures of the drawing.

As illustrated, a connecting rod 1 is attached to the crank pin 2 of a revoluble crank 3 and my improved grease cup 4 is attached to a strap 5 and is adapted to supply lubricant to the bearing 6 and pin 2.

Rotation of the crank imparts sudden reverse movements to the cup 4, to withdraw the plunger wholly out of said passage 6, to admit the lubricant to flow therein, and to project the plunger into and through said passage to positively discharge the lubricant therefrom.

The cup 4 is hollow so as to contain a suitable supply of lubricant and the lower internal portion of the cup 4 is preferably inclined or conical, as indicated by 5', and terminates in a discharge passage 6'. The discharge passage 6' is provided with a shoulder 7 near its lower discharge end 8. The exterior of the cup is reduced to provide a stem which is threaded, as indicated at 9, and which may be provided with a

polygonal nut 10 by means of which the cup may be threaded or turned home in the strap 5 and bearing 6. The top of the cup 4 is open and may be provided with a cap 60 or closure 11 and the latter is provided with a guiding portion in the form of a sleeve 12.

A plunger 13, which performs the function of a feeder, is slidably mounted in the guiding sleeve 12 and closely fits the discharge passage 6'. The guiding sleeve 12 is of sufficient length to guide the feeder 13 throughout its travel and the shoulder 7 conveniently forms a stop limiting movement of the feeder in one direction.

The operation is as follows:—When a to and fro movement, which in the present specific embodiment is an up and down movement, is imparted to the lubricant cup 4, by rotation of the crank 3, then, an up and down movement is imparted to the feeder 13 and the lubricant is forced downwardly through the passage 6. The feeder 13, which may be in the form of a solid rod, is of sufficient weight to acquire considerable 75 momentum so that a positive feed action will be obtained. Upon downward movement of the crank 3 the feeder rod 13 will be moved downwardly into the passage 6 and by reason of the fact that the passage 6 is of a pre-determined size, it will be understood that the feeder 13 will, at each stroke, feed a selected quantity of lubricant. The up stroke of the part due to upward movement of the crank will retract the feeder 13 into 80 the position shown in Fig. 2. It will also be understood that during co-movement of the crank, or other parts which may actuate the feeder, no appreciable amount of the lubricant will be fed. When the crank or 85

other parts attain sufficient speed to impart a to and fro movement to the feeder then the feed of the lubricant will be initiated and maintained and such feed will not be dependent upon the quantity of lubricant in 100 the cup, so long as there is a sufficient quantity to maintain a level above the passage 6. It will also be understood that the feed of the lubricant increases and decreases in accordance with the speed of the crank 105

3 by reason of the fact that during a relative slow rotation the feeder 13 will not be actuated with the same force and therefore will not drive out as much lubricant from the cup as would be the case if the crank 3 110 was rotated at a higher speed.

While I have herein shown and described

one specific embodiment of my invention, I do not wish to be limited thereto except for such limitations as the claims may import.

I claim:

5. 1. A grease cup comprising in combination, a casing and a plunger adapted to reciprocate in said casing, said casing being provided with an inner chamber which tapers downwardly and which is provided with a discharge chamber opening directly out of the lower end of said tapered portion, the walls of said discharge chamber intersecting the tapering walls of said inner chamber and the connection between said 10 chambers being entirely uninterrupted, and said plunger being arranged to reciprocate in said last mentioned chamber and to lift entirely out of said last mentioned chamber at one end of its stroke.
15. 2. A grease cup comprising in combina- 20

tion, a casing, a cap for said casing, a guide rigid with said cap, and a plunger adapted to reciprocate in said casing and engaging said guide, said casing being provided with an inner chamber which tapers downwardly and being provided with a discharge chamber opening directly out of the lower end of said tapered portion, the walls of said discharge chamber intersecting the tapering walls of said inner chamber and the connection between said chambers being entirely uninterrupted, and said plunger being so arranged as to move into and entirely out of said discharge chamber. 25 30

In testimony whereof I affix my signature in presence of two witnesses.

WALTER L. STINE.
